UNITED STATES PATENT OFFICE

141,288

DESIGN FOR A HUB CAP OR SIMILAR ARTICLE

George Albert Lyon, Allenhurst, N. J.

Application July 29, 1944, Serial No. 114,617

Term of patent 14 years

(Cl. D14—30)

To all whom it may concern:

Be it known that I, George Albert Lyon, a citizen of the United States and a resident of the village of Allenhurst, in the county of Monmouth and State of New Jersey, have invented a new, original, and ornamental Design for a Hub Cap or Similar Article, of which the following is a specification, reference being had to the accompanying drawing, forming a part thereof.

On the drawing:

Figure 1 is a side elevational view of a hub cap showing my new design.

Figure 2 is a profile view showing the cross sectional contour of the hub cap, which comprises an outer annular portion A, a central portion B and a beaded portion C.

I claim:

The ornamental design for a hub cap or similar article, as shown and described.

GEORGE ALBERT LYON.
